UNITED STATES PATENT OFFICE.

EDWIN BIRD WILSON, OF FOREST HILLS, NEW YORK.

DESIGN FOR A CHAIR OR SIMILAR ARTICLE.

Application filed July 24, 1923. Serial No. 6,844. Term of patent 14 years.

To all whom it may concern:

Be it known that I, EDWIN BIRD WILSON, a citizen of the United States, residing at Forest Hills, Queens County, and the State of New York, have invented a new, original, and ornamental Design for Chair or Similar Article, of which the following is the specification, reference being had to the accompanying drawing, forming part thereof.

The figure is a front view of a piece of furniture, in the present case a chair, showing my new design.

I claim:

The ornamental design for a chair or similar article as shown.

EDWIN BIRD WILSON.
